WRITING INSTRUMENT

Nathan Zepelovitch, Tel Aviv, Israel, assignor to
Nahum A. Bernstein, New York, N. Y.

Application July 12, 1949, Serial No. 104,314

4 Claims. (Cl. 120—46)

1

The invention relates to writing instruments of the fountain pen type, i. e. to instruments having an ink reservoir. More particularly the invention relates to such instruments where the ink reservoir is constituted by the rigid barrel of the instrument.

The "sweating" of such instruments is a frequent occurrence and has always been considered a nuisance. This wetting of the penholder, particularly at the spot where it is usually held by the fingers of the writing hand, is due to the fact that after writing, traces of ink remain in the nib and feed duct, or for that matter in the writing tip if there is no nib proper, and owing to changes of temperature (e. g. the difference between outside temperature and the body temperature inside the pocket), these traces of liquid evaporate, later on condense and collect on the inside of the cap and seep downwards onto the neck of the holder. Another cause for this occurrence may be changes of outside pressure to which the instrument is exposed, e. g. as in the case of air travels.

It is the object of this invention to create a writing instrument of the type having an ink reservoir, wherein the above described drawback is eliminated. To this end the instruments are provided with means which cause the writing tip and feed duct to be subjected to a suction from the ink reservoir every time the writing is interrupted and the instrument is reversed from the writing position into a position with its writing tip pointing upwards.

In order that the invention should be more readily understood, I shall describe it now with reference to the accompanying drawings showing by way of example a writing instrument of the type indicated above and having a narrow tube as writing tip. Although my invention is most advantageously applied to this type of instrument, I wish it to be understood that the invention is not limited thereto and that it can be applied to any type of fountain pen having a rigid ink reservoir and wherein the accommodation of the new means is not obstructed by parts of the filling mechanism, such as pistons and the like.

Fig. 1 is a schematic view, partially in section, of a writing instrument of the kind referred to;

Fig. 2 is a vertical section, enlarged in scale, of the upper portion of the writing instrument illustrated in Fig. 1;

Fig. 2a shows the construction illustrated in Fig. 2 but reversed in position, i. e. disposed upside down; and

2

Fig. 3 is an enlarged vertical sectional view of an alternative construction.

Referring now to Figs. 1 and 2:

There is provided a writing instrument having a barrel 1 constituting the ink reservoir. Disposed within the barrel 1 and secured to the end thereof opposite the writing tip is a soft and resilient bag 2 made of air and watertight material. To the side of the bag disposed towards the writing tip, a weighted body 3, e. g. a small metal pellet, is fixedly attached. The bag 2 is in communication with the atmosphere through a small hole 4 extending through the wall of the ink reservoir.

15 While in writing position, due to the weight of pellet 3, the bag 2 is expanded to its full volume. As soon as the writing is stopped and the instrument is reversed, it assumes the position shown in Fig. 2a, and due to the weight of pellet 3 the bag 2 collapses and folds up, with the consequence that suction is created within barrel 1, sufficient to suck moisture from the writing tip and ink feed duct back into the barrel. Contrarily, when writing is resumed, the bag 2 20 presses forward and assumes a configuration as shown in Figs. 1 and 2, and a small quantity of ink is immediately forced to the writing tip and writing can be commenced at once. Thus, whenever the bag expands, air enters through hole 4 and at its collapse, air is expelled through the hole, not restricting the movement of pellet 3 25 which is conditioned solely by its own weight.

The bag should be soft and yielding to a very slight weight, so that the pellet need not be of great size. I have found a latex bag gives the best results, the pellet being of lentil size.

According to Fig. 3, a membrane 5 is cemented to the inner wall of barrel 1, across its width and some distance from its rear end. The centre of 35 this membrane or diaphragm is weighted by a metal pellet 6. In this case there is no communication between the space 7 divided off from the barrel by the diaphragm, and the outside. Thus within space 7 a quantity of air is enclosed. When the instrument is brought into writing 40 position the diaphragm will bulge downward, i. e. towards the tip, and with the tip pointing upwards the bulge will be downward, but in this case towards the rear end of the instrument. 45 These movements are of course of smaller magnitude and effect than those of the bag mentioned in the description relating to the embodiment shown in Figs. 1, 2 and 2a.

The determination of whether one or the other 50 of these constructions will actually be chosen for

an individual type of writing instrument will depend upon the width of the ink outlet, the density of the ink and similar considerations.

With the diaphragm construction illustrated in Fig. 3, the air, due to its resistance against expansion and compression and due to its being enclosed in space 7, serves as a brake for the movement of the membrane, thus slowing down this movement.

I claim:

1. In a writing instrument, a barrel member adapted to contain a writing fluid, a writing tip mounted on one end of said barrel member and in fluid communication with the interior thereof, easily deformable material forming a compartment positioned within said barrel member at the end thereof opposite said writing tip, and a small weighted member of a mass sufficient to deform said deformable material upon gravitational displacement thereof disposed entirely within said barrel member and secured to said compartment on the portion thereof nearest said writing tip for varying the pressure in said barrel in response to the relative elevation of said writing tip with respect to said barrel member under the influence of gravitational displacement of said weighted member deforming said compartment.

2. In a writing instrument, a barrel member adapted to contain a writing fluid, a writing tip mounted on one end of said barrel member and in fluid communication with the interior thereof, easily deformable material forming a compartment positioned within said barrel member at the end thereof opposite said writing tip, passage means connecting the interior of said compartment with the atmosphere externally of said barrel, and a small weighted member of a mass sufficient to deform said deformable material upon gravitational displacement thereof disposed entirely within said barrel member and secured to said compartment on the portion thereof nearest said writing tip, whereby the pressure in said barrel is varied in response to the relative elevation of said writing tip with respect to said weighted member through the gravitational displacement of said weighted member deforming said compartment.

3. In a writing instrument, a barrel having an ink reservoir therewithin, a writing tip in fluid communication therewith, and means for varying the pressure in said ink reservoir in response to the relative elevation of said writing tip with respect to said ink reservoir, including a deformable diaphragm forming the boundary of said ink reservoir positioned opposite to said writing tip and a small weighted member of a mass sufficient to deform said deformable diaphragm upon gravitational displacement thereof disposed entirely within said barrel and secured to said deformable diaphragm for deforming the same in response to the gravitational displacement of said weighted member.

4. In a writing instrument, a barrel having an ink reservoir therewithin, a writing tip in fluid communication therewith, and means for varying the pressure in said ink reservoir in response to the relative elevation of said writing tip with respect to said ink reservoir, including deformable material positioned entirely within said barrel and forming with the adjacent portions of said barrel a deformable compartment in communication with the atmosphere externally of said ink reservoir, and a small weighted member of a mass sufficient to deform said deformable material upon gravitational displacement thereof disposed entirely within said barrel and secured to said deformable material for deforming the same in response to the gravitational displacement of said weighted member.
